Term of patent 3½ years

(Cl. D45—4)

FIG. 1

FIG. 2

FIG. 3

FIG. 4

FIG. 5

Figure 1 is a top plan view of an expansible chain for a bracelet or similar article embodying my new design with the links shown in contracted position;

Figure 2 is a view similar to Figure 1 with the links in expanded position, portions of the back links being visible between expanded links and shown in dotted lines;

Figure 3 is an enlarged top plan view of a single top link of the expansible chain;

Figure 4 is an elevational view looking from right to left at the link shown in Figure 3, and

Figure 5 is an edge elevational view looking from the bottom edge to the top edge of the link shown in Figure 3.

The characteristic features of my design reside in those portions shown in full lines.

I claim:

The ornamental design for an expansible chain for a bracelet or similar article, substantially as shown and described.
